UNITED STATES PATENT OFFICE.

JENS N. CHRISTENSEN, OF CHICAGO, ILLINOIS.

TEMPORARY BINDER.

No. 813,948.

Specification of Letters Patent.

Patented Feb. 27, 1906.

Application filed April 10, 1905. Serial No. 254,871.

To all whom it may concern:

Be it known that I, JENS N. CHRISTENSEN, a citizen of the United States, residing at Chicago, in the county of Cook and State of Illinois, have invented new and useful Improvements in Temporary Binders, of which the following is a specification.

This invention relates to that class of devices known as "temporary binders" for periodicals, journals, papers, and the like; and the object is to provide a binder of the above-described character with simple and convenient means whereby the binder may receive additional papers and gradually have the oldest ones extricated without interfering with the remaining papers.

With this object in view the invention will be hereinafter fully described and claimed.

In the accompanying drawings, forming part of this specification, and in which similar letters of reference indicate corresponding parts, I have illustrated an embodiment of my invention, it being understood that other forms of embodiment thereof may be employed without departing from the spirit of same.

Referring to the accompanying drawings, Figure 1 is an inner view in elevation of a binder embodying my invention, showing it open. Fig. 2 is a cross-sectional view of the binder, showing the covers closed and illustrating a number of papers held in place therebetween, said section being taken on line *ff* of Fig. 1. Fig. 3 is a longitudinal sectional view through binding-strip *b*, showing the cord-tip and a portion of the cord located in position thereon, said section being taken on line *g*, *g* of Fig. 1; and Fig. 4 is a detached perspective view of one of the cord-tips and a portion of one of the cords.

In the drawings the reference-letters *a* and *a'* designate the covers, which are preferably made of cardboard and have hinged to their rear edges, by means of cloth or other flexible material, binding-strips *b* and *b'*, made of any suitable material, but preferably of cardboard reinforced by a metal strip on their inner sides. The binding-strips have perforations, and the strip *b'* carries fasteners *c*, preferably made of spring-wire bent to form two

coils. Connecting the two binding-strips are cords *d*, each of said cords having at one end a metal tip *e*, about one-half of which is of a half-tubular shape, as at *e'*, while the other portion thereof is made full tubular in shape and secures one end of the cord, so that the portion of the same adjacent to the secured end thereof may be placed in or removed from the half-tubular portion. The other end of each cord is provided with a pointed puncturing metal tip or needle *c'* to pierce the papers when the same are being filed.

It will be understood that the papers or other documents are secured between the opposite surfaces of the binding-strips *b* and *b'* and that the cords *d* will pass through the inner margins of the papers, as is clearly shown in Fig. 2 of the drawings, in which figure it will be observed that the binding-strips *b* and *b'* are bent back so as to lie on the inner surfaces of the covers *a* and *a'*, respectively, so that when the cords are drawn taut and secured to the fasteners *c* on the strip *b'* the cord-tips *e* will lie longitudinally on the binding-strip *b* within the grooves *h*, provided in the strip *b* for the reception of said cord-tips, as is clearly shown in Figs. 1 to 3 of the drawings. The grooves *h* are employed to prevent the cord-tips *e* from moving sidewise, and it is apparent that instead of having two grooves, as shown in Fig. 1 of the drawings, a groove extending the entire length of the strip *b* may be employed.

When it is desired to remove the papers, the cords *d* are disengaged from the fasteners *c* on the strip *b'*, when by pulling on the tips *e* the cords may be partially drawn through the papers and openings in the covers, so that the portion of each cord adjacent to the end thereof secured in the tip *e* may be placed in the half-tubular portion *e'* of each tip, when it may be passed through the binding-strip *b*, and thus allow the papers to be removed over the tips.

Having thus fully described my invention, what I claim as new, and desire to secure by Letters Patent, is—

A temporary binder consisting of two covers, a binding-strip flexibly connected to the rear edge of each cover and having a number

2
of openings, fasteners secured on one strip, cords adapted to pass through said openings and connect the strips, each cord having at one end a metal retaining-tip, a portion of each of said tips being formed in cross-section

5 into a half-tubular shape and the other portion of each tip being formed into full tubular shape and adapted to engage one end of the

10 cords the other ends of the cords being adapted to engage said fasteners, substantially as described.

JENS N. CHRISTENSEN.
